LUBRICATING SYSTEM

Original application filed January 12, 1928, Serial No. 246,213. Divided and this application filed November 1, 1928. Serial No. 316,456.

This invention relates to lubricating systems and more particularly to those for internal combustion engines of the rotary type, and has for its object to provide a construction which will be simple in parts and more efficient in use than those heretofore proposed.

With these and other objects in view the invention consists in the novel details of construction and arrangements of parts as will be more fully disclosed hereinafter and particularly pointed out in the claims.

This application constitutes a division of my copending application filed January 12, 1928 under the Serial No. 246,213 for improvements in internal combustion engines.

Referring to the accompanying drawings forming a part of this specification in which like numerals designate like parts in all the views,

Fig. 1 is a vertical sectional view taken through an engine to which this invention has been applied;

Fig. 2 is a transverse sectional view taken as on the line 2—2 of Fig. 1 and looking in the direction of the arrows;

Fig. 3 is a vertical transverse sectional view of the oil feeding means taken as on the line 3—3 of Fig. 4 and looking in the direction of the arrows; and

Fig. 4 is a vertical sectional view taken longitudinally of the engine showing the means for supplying oil for lubricating the engine.

Briefly this invention covers a lubricating system which may be used in connection with, for example, an internal combustion engine of the rotary type, consisting of a plurality of cylinders (four being indicated in the drawings) suspended in frames and attached to a valve housing casting to which the valves, spark-plugs, valve pistons, lubricating agitators, and lubricating pumps are attached. Also to the said frames are attached wheel pinions, each adapted to be driven by a piston pitman, said wheels being in mesh with a ring gear rigidly carried by the stationary housing of the engine. Suitable cams are provided upon a semi-stationary reversing plate mounting at the opposite end of

the casing for actuating the valves and their stems and also carried by said mountings are the means for creating the electrical contact for firing the charge of combustible fluid used to drive the engine. The exhaust gases from the cylinders are collected in an annular chamber adapted to register with suitable exhaust ports in said engine housing. The means for lubricating the moving parts of the engine is controlled and actuated by the reciprocations of the valve stems, and the lubricant used further aids in cooling the valve parts.

Referring more particularly to Fig. 1 the main shaft of the engine is represented by the numeral 1 and the engine housing 2. Secured to one end plate 3 of said housing as by the bolts 4 and concentrically disposed with respect to said main shaft is a bevelled ring gear 5 meshing with bevelled gear pinions 6 each mounted on a stub 7 carried by a casting 8 rigidly disposed on the shaft 1. To each gear pinion 6 (of which there are as many as there are cylinders to the engine) is secured an outwardly extending crank pin 9 adapted to receive one end of a pitman 10 the other end of which is mounted on the usual wrist-pin carried by the piston 11 operating in a cylinder 12.

Thus it will be seen that as the piston reciprocates in the cylinder, the pitman associated therewith will drive its gear pinion which is in mesh with the ring gear 5, and since the ring gear is rigidly secured to the engine housing and therefore stationary, the gear pinions will be caused to "walk" around said ring gear, thus imparting a rotary motion of the engine with respect to the axis of the main shaft 1.

The cylinders 12 are mounted in a plurality of parallelly disposed frames or bails generally indicated by the numeral 15 which are rigidly mounted on the main shaft 1 with suitable spacers 16 between each adjacent pair of frames, see Fig. 1. Thus it will be seen that a plurality of cylinders can be supported by the plurality of frames 15 in any particular angular relation and in conformity with the type of engine desired. In the particular engine illustrated in the drawings, there are

indicated four cylinders spaced 90° apart but it is evident that a greater or less number may be employed with appropriate angular spacing therebetween.

Rigidly disposed on the main shaft 1 is a heavy casting 20, see Fig. 1, which serves not only as a cylinder head and the intake manifold for the engine but also serves as a valve housing. That is to say, this plate or casting 20 is cruciform in shape or in other words, comprises a main central portion with radial extensions or arms 21, one for each cylinder, and the end of each extension is circular as indicated at 22 to provide a cap or head for each cylinder, see Fig. 3. The casting 20 besides being mounted on the shaft 1 for rotation therewith is secured by a plurality of tie rods 23 of sufficient length to pass through the plurality of frames or bails 15, to the casting 8 which carries the gear pinions 6.

Any suitable means of securement may be utilized, such for example as threading one end of the tie rods into the cylinder head 20 and applying a nut to the other end of each tie rod to draw the members 8, 15, 16 and 20 into tight immovable unity. Secured to said cylinder head as by the bolts 24 is a heavy template collar 25, any suitable packing being provided between said head and collar for making this joint leak proof.

The construction of each extension 21 of the valve housing casting 20 is clearly shown in Figs. 1 and 4. In other words, said casting is cored to provide the exhaust chamber 30 at the extreme end portion of each extension 21 which is separated from the intake chamber 31 as by the wall 32. The inner surface of the exhaust and inlet chambers is curved as shown in Fig. 4 to more readily direct the intake and exhaust gases to and from each cylinder so that there may be a substantially unobstructed flow of these gases. The location of the wall 32, which partakes of the nature of a superheater for the incoming fuel, is axial with respect to each cylinder, and on either side of said wall is disposed a valve. The construction will be readily understood with particular reference to the figures of the drawings wherein it will be seen that the valve 33 controls the inlet of fresh fuel for combustion, and the valve 34 controls the exhaust of the burned gases from the cylinder, said exhaust gases passing from the chamber 30 into the annularly formed exhaust manifold 35 which is of substantially U-shaped formation and adapted to rotate with the cylinder head 20.

Each valve is provided with a stem, see Fig. 4, the extreme end of which is screw threaded into a valve piston. In other words, the inlet valve 33 has a stem 36 (having sliding engagement with the valve guide 37 carried by the cylinder head 20) which extends beyond its guide, the end being screw threaded into the cylindrical piston 40. To

insure the seating of the valve 33 there is disposed a coil spring 41 between the valve guide 37 and the inner cylindrical wall of the piston 40. The head or closed end of the piston 40 is provided with a yoke 42 carrying a pin 43 on which is rotatably mounted a roller 44 adapted to contact with a cam track such as 45 during the travel of said roller about the shaft 1. In like manner the valve 34 is provided with a stem 50 passing through a valve guide 51 carried by the cylinder head 20, said stem having secured to its end a piston 52 between which and the guide 51 is disposed a coil spring 53. The end of the piston 55 is likewise provided with a yoke 54 carrying a pin 55 on which is rotatably mounted a roller 56 adapted to contact with a cam track such as 57 as said roller is carried around during the rotation of the engine. It should be stated, however, that the cam tracks 45 and 57 while concentrically disposed are not located to simultaneously operate the two valves 33 and 34, the cam track 45 being in advance of the track 57. Therefore, the track 45 which would not ordinarily be seen in Fig. 1 has been indicated in dotted lines.

Each arm 21 of the cylinder head 20 is provided with a bore constituting an oil conduit 60 for each cylinder, said conduit extending to the outer end of each arm and provided with a plurality of enlarged portions to receive ball valves for controlling the flow of oil in said conduit. In other words, there is provided a ball valve 61 disposed on the outer side of the exhaust valve, a ball valve 62 disposed between the intake and exhaust valves, and a third ball valve 63 disposed between the intake valve and the tie rods associated with the cylinder head 20.

Each ball is spring pressed as shown, the springs being so disposed as to permit passages of lubricating oil in a direction toward the main shaft 1 of the engine only. The extreme outer end of the conduit 60 is provided with any suitable device to scoop a quantity of oil from the sump and to direct the same to said conduit. In Figure 3 is shown one form of such a device, the same consisting of a tube 64 provided with a plurality of small apertures 65, said tube being diametrically split beyond said apertures to form two portions of the tube each of which is outwardly curved and bent to form the scoops 65 and 67 which, as the engine rotates, dip a slight distance below the sump oil level indicated at 68.

The method of lubricating the engine consists in scooping a small quantity of oil by either the member 66 or 67, according to the direction of rotation of the engine, and this oil will be forced toward and through the small apertures 65 to the interior of the tube 64. This action is augmented by the reciprocations of the exhaust and intake valves with their associated pistons 52 and 40 respectively. In other words, and with more

particular reference to Fig. 4 it will be seen that during the rotation of the engine about the main shaft 1, the valve roller 56 will ride off its associated cam track 57 whereupon the spring 53 will force the exhaust valve 34 to its seat. In this movement, however, the piston 52 carried by the valve stem 50 will have moved to the left as seen in said figure and created a suction in the space within said piston. This suction is sufficient to draw oil past the ball valve 61 and into the piston chamber.

When the exhaust valve is forced to open position by its roller 56 again contacting the cam track 57, then the piston 52 is moved toward the right as seen in said figure and this movement will force oil within the piston chamber past the intermediate ball valve 62 and into the chamber of the piston 40 of the intake valve 33. If said chamber is already filled with oil, some oil will be forced past the innermost ball valve 63 into the conduit 60. This pumping of the oil is thus seen to be alternately accentuated by the movements of the valve pistons 52 and 40 so that said oil is circulated through the cylinder head 20, cooling the same as well as the valve stems and guides therefor.

The innermost end of the conduit 60 terminates in substantially the line of the tie rods 23 holding the cylinders and adjacent portions of the engine together, and said terminus connects with the bore of one of said tie rods by a cross-passageway 69 drilled in the cylinder head 20. A screw plug 70 is provided in the outer extremity of said passageway to prevent the escape of oil therethrough. One of the recesses in the cylinder head 20 to receive a tie rod 23 is slightly enlarged as at 71 to insure registry of a diametric bore 72 adjacent the end of said tie rod, and this diametric passage is in open communication with a central bore 73 in said tie rod. In other words, each tie rod 23 is provided with an axial bore 73 communicating with a transverse bore 72 near one end, said transverse bore of one tie rod associated with each cylinder adapted to be in direct communication with the lubricating conduit 60 in the cylinder head 20, so that oil pumped by the valve pistons will pass through said tie rod.

The other end of the lubricant-conveying tie rod is connected as by the pipe conduit 74 to the parts requiring lubrication. In Fig. 1 said conduit 74 is shown leading to the bearing 75 for the bevelled gear pinion 6 and it will be readily understood that oil delivered to said bearing will seep therefrom and properly lubricate not only the pinion 7, but the gears 6 and 5 and will pass, by means of a collector ring cut on the face of gear 6, to and through a conduit 76 to collector rings on the bearing face of the pitman 10, said rings communicating with

the trunnion 9 on which said pitman rides.

Near one end of the casing 2 and rigid therewith is a vertical wall generally indicated by the numeral 80 adapted to carry the cam tracks for controlling the movements of the cylinder valves. This wall comprises a stationary upper portion, a stationary lower portion, and a central movable portion comprising the slide 83 provided with a central elongated slot through which passes the main shaft 1. The cam track 45 is mounted on the slide 83 whereas the cam track 57 is mounted on the lower portion of the wall 80. The tracks are made of such lengths as to insure contact with the rollers 44 and 56 for a time sufficient to hold the valves 33 and 34 open for the passage of the inlet and exhaust gases, and further are so positioned on their supporting members that said valves will be operated in proper sequence. Provision is made for shifting the slide 83 to move the cam track 45 out of, and to bring a similar auxiliary cam track (not shown herein) into, operative registry with the roller 44 when a reversal of the directional rotation of the engine is desired.

In a copending application, of which this is a division, the other features of this rotary engine were fully set forth and described, but reference to a few of said features follow in order that the operation of said engine may be better understood.

This particular engine however, is only illustrated and described as one example of a mechanism to which this lubricating system is applicable since the principles of said system are such that its employment may be extended to other mechanisms.

A cam 98 also carried by the slide 83 extends into the rotary path of the carburetors 100 of which there is one for each engine cylinder, said cam being for the purpose of actuating successively the piston of each carburetor to eject the fuel therefrom into the chamber 31 therefor. The fuel is fed to the engine from a source of supply through the conduit 105 to a stationary distributor ring 106 surrounding the main shaft 1, and feeds from said ring radially into a chamber 128 within said shaft from which it passes into the chamber of each carburetor by the action of its piston as well as by centrifugal force. The cam 98 is adjustably mounted on the slide 83 for positions in accordance with the directional rotation of said engine.

The upper portion of the wall 80 carries two electrical contact members such as shown at 150 either of which can be swung to assume different operative positions in the circular path of companion electrical contact members 154, of which there is one for each engine cylinder, each member 154 being electrically connected to a spark plug 155. The advancement or retardation of the time of the spark with relation to the rotation of

the engine is varied through the swing of each member 150. It should be stated that only one of the members 150 is in use at a time, the other being moved out of said circular path. The desired directional rotation of the engine will govern which of the members 150 is to be used.

At the bottom of the casing 2 surrounding the engine there is provided a sump 157 adapted to contain the lubricating oil, and provided with a casting 160 of trough-like shape and extending upwardly to meet the extending circumferential edges of the exhaust manifold 35, so that the exhaust gases may be delivered exteriorly of the engine casing. The annular exhaust chamber 35 is adapted to rotate with the engine between suitable seals carried by the casing, such for example as shown at 161 in Fig. 1, and leakage of the exhaust gases into the engine casing at the lower portion thereof is prevented by side plates 162 covering the joint between the exhaust chamber 35 and the sump casting 160.

The casing 2 is provided with a bearing for receiving the shaft 165 of a starting motor, not shown, said shaft having mounted thereon a pinion 166 meshing with a ring gear 167 mounted circumferentially of the cylinder head 20, and said casing is provided with suitable bearings such as indicated at 168 and 169 within which the main shaft 1 rotates.

Thus it will be seen by this invention there is provided a lubricating system for mechanisms such for example as engines of the internal combustion type, the example shown in the drawings being such an engine of the rotary classification. This method of lubrication consists in abstracting a portion of the lubricant from a source of supply which is accomplished by the scoops 66 or 67 dipping into the oil of the sump. The remainder of the method comprises feeding this lubricant so obtained to the parts to be lubricated while preventing natural retro-flow of said lubricant.

By this is meant that the scoop abstracts a small portion of oil from the sump and in the revolution of the engine proper the scoop with its oil is carried upwardly in a circular path, the oil being prevented from leaving the scoop due to the trough-like construction of the latter. When the scoop arrives at a certain point in its circulatory orbit the oil will reach the apertures 65, pass therethrough and by this time the exhaust valve 35 will become operative to cause the piston 52 associated therewith to create a suction which will draw the oil which has just passed through the apertures 65 into the conduit 60 and pass the check valve 61. Upon the opposite movement of said piston 52 the oil entrapped within the cylinder thereof will be forced past the check valve 62 into the cylinder in which operates the piston 40 of the other or intake valve of the engine, and a reverse flow of

the lubricant is prevented by the aforementioned check valve 61. In this connection it might further be stated that due to the rotation of this engine, centrifugal force will prevail which will have a large tendency to cause the lubricant within the conduit 60 to move axially thereof in a direction toward the scoop 66 and 67, as will be evident and therefore the several check valves 61, 62 and 63 perform a dual function of preventing this natural flow of lubricant in a direction which is opposite to the direction of flow which is desired. Ultimately the lubricant reaches and passes through the conduit 73 within the tie rod 23, enters the bearing 75, spreads over the face of the bevel pinion 6, is thrown by centrifugal action to the peripheral teeth thereof to thus lubricate the ring gear 5 and pitman pinion 9.

The centrifugal action caused by the bevel pinion 6 throws lubricant into the interior of the cylinder 12 to lubricate the piston 11 thereof. Also it is obvious that the oil is utilized for lubricating the pistons 40 and 52 as well as the stem guides 37 and 51 of the valves 33 and 34.

It is obvious that those skilled in the art may vary the details of construction and arrangements of parts constituting the apparatus as well as the steps and combinations of steps constituting the method of lubrication without departing from the spirit of this invention and therefore it is not desired to be limited to the foregoing except as may be required by the claims.

What is claimed is:

1. In a rotary engine the combination of a cylinder provided with a head; a valve movable with said cylinder; a conduit associated with said cylinder; means to furnish lubricant to said conduit; and means within the cylinder head to force said lubricant through said conduit said means controlled by the actuation of said valve.

2. In a rotary engine the combination of a cylinder provided with a head; a valve movable with said cylinder; a conduit associated with said cylinder; means carried by said cylinder head to furnish lubricant to said conduit regardless of directional rotation of said engine; and means to force said lubricant through said conduit said means controlled by the actuation of said valve.

3. In a rotary engine the combination of a cylinder; a valve associated with said cylinder; a conduit associated with said cylinder; means comprising a scoop to furnish lubricant to said conduit; and means to force said lubricant through said conduit controlled by the actuation of said valve.

4. In an engine the combination of a cylinder; a valve associated with said cylinder; a conduit associated with said cylinder; means comprising a bifurcated tube with oppositely turned ends to furnish lubricant to

said conduit; and means to force said lubricant through said conduit controlled by the actuation of said valve.

5. In an engine the combination of a cylinder; a valve associated with said cylinder; a conduit associated with said cylinder; means comprising a bifurcated tube with oppositely turned ends and an aperture in the cylindrical portion to furnish lubricant to said conduit; and means to force said lubricant through said conduit controlled by the actuation of said valve.

10. In an engine the combination of a cylinder provided with a head; a valve associated with said cylinder; a conduit associated with said cylinder; means to furnish lubricant to said conduit; and means comprising a piston within the cylinder head to force said lubricant through said conduit controlled by the actuation of said valve.

15. In an engine the combination of a cylinder provided with a head; a valve associated with said cylinder; a conduit associated with said cylinder; means to furnish lubricant to said conduit; and means within the cylinder head and including a ball check in said conduit and a piston coaxial with said valve to force said lubricant through said conduit.

20. In an engine the combination of a plurality of cylinders joined to a common rotatable head; a valve for each cylinder in said head; a conduit for each cylinder in said head, said conduits for conducting lubricant to said cylinders; and means carried by said head for supplying lubricant to and through each conduit.

25. In an engine the combination of a plurality of cylinders joined to a common rotatable head; a valve for each cylinder in said head; a conduit for each cylinder in said head, said conduits for conducting lubricant to said cylinders; and separate means carried by said head for supplying lubricant to and through each conduit.

30. In an engine the combination of a plurality of cylinders joined to a common rotatable head; a valve for each cylinder in said head; a conduit for each cylinder in said head, said conduits for conducting lubricant to said cylinders; and means carried by said head for supplying lubricant to and through each conduit separately.

35. In testimony whereof I affix my signature.
HERMAN A. FINKE.
